UNITED STATES PATENT OFFICE.

MATTHEW H. REED, OF ALLEGHENY, PENNSYLVANIA.

INDICATING AND RECORDING SCALE.

SPECIFICATION forming part of Letters Patent No. 642,756, dated February 6, 1900.

Application filed August 15, 1896. Serial No. 602,891. (No model.)

To all whom it may concern:

Be it known that I, MATTHEW H. REED, a citizen of the United States, residing at Allegheny, in the county of Allegheny and State 5 of Pennsylvania, have invented or discovered new and useful Improvements in Indicating and Recording Scales, of which the following is a specification.

In the accompanying drawings, which make 10 part of this specification, Figure 1 is an elevation of the scale-beam. Fig. 2 is an elevation of the combined poise and card-holder, showing a portion of the beam. Fig. 3 is a 15 cross-section along line *a a* in Fig. 2. Fig. 4 is a front elevation of the counterpoise, showing card-holder and a weight in position. Fig. 5 is a cross-section along the line *b b* in Fig. 4. Fig. 6 shows the recording-card used 20 in this form of my device. Fig. 7 shows my invention adapted to compound beams, the beam in the figure being a railway-scale beam with the card-holder removed to show arrangement of beams. Fig. 8 is a cross-section 25 along the line *c c* in Fig. 7. Fig. 9 is a sectional plan view along the line *d d* in Fig. 8. Fig. 10 shows the recording-card used in this 30 form of my invention. Fig. 11 shows a modification of the secondary-poise mechanism shown in Fig. 7 with card-holder removed. Fig. 12 is a cross-section along the line *e e* in Fig. 11, and Fig. 13 shows the form of recording-card used in this form of my device. Figs. 6, 10, and 13 are drawn full size for the 35 sake of clearness. The remaining figures are half-size. Fig. 14 is a single assembled figure showing the beam with a poise and weight carrying counterpoise-hanger mounted thereon.

The purpose of my invention, generally 40 stated, is to provide a reliable indicating and recording device for scales.

The following is a detailed description of my invention:

1 is a graduated scale-beam preferably 45 made with parallel edges.

2 is a poise mounted on beam 1 and adapted to be used as a card-holder.

3 is the guide-plate of poise 2.

4 is a filler holding poise 2 steady on beam 1.

5 is the front plate of poise 2, screwed to 50 guide 3 through lugs 6 and cut away at the

top to permit the insertion of card between it and beam 1. Push 7 is attached to plate 8, the face of which is provided with a backing of rubber or any other suitable substance 9. On 55 the stem of push 7 is spring 10, which retains plate 8 normally against plate 5. In recording weights the card is inserted between backing 9 and the beam 1, against which it is advanced by pressing push 7, the spring of the 60 card being sufficient to throw the card away from beam 1 when push 7 is released.

11 11 are a series of puncturing-pins fixed on the face of beam 1, the first pin to the left of the series being so placed as to register 65 "0" on card 12 when the poise 2 indicates "0" on beam 1 and the card is in position in the card-holder. The pins 11 11 are spaced apart a distance equal to one hundred pounds on the graduations on the scale-beam, each 70 succeeding pin, beginning at the left, having a predetermined rise above the preceding one—as, for instance, one-eighth of an inch, as in Fig. 1.

12 is a card fitted to be inserted in poise 2 75 and on its lower half 12^a to receive the imprint of pins 11 11. The horizontal lines on 12^a are spaced apart the same distance as the vertical rise of pins 11 11, while the vertical lines on 12^a correspond to the graduations on 80 the beam 1. It will thus be seen that the horizontal lines on 12^a will indicate hundreds and the vertical lines tens and subdivisions thereof.

Counterpoise 13 is mounted on stem 14. 85 Card-holder 2^a slides on guide-bar 15 by means of guides 16 16, guide-bar 15 being fixed to counterpoise 13 by bolt 17 and to stem 14 by cross-bar 18.

15^a is a spring pawl or catch by which card-holder 2^a is held up while the counterpoise 13 is being loaded with weights. Card-holder 2^a is preferably constructed of flexible material, so that it may be pressed against pins 11^a 11^a, and is provided with a suitable backing, as rubber 2^b. 90

19 is a rider fixed to card-holder 2^a in such a position as to rest on counterpoise 13 when no weights are placed thereon and adapted to rest upon the weights and raise card-holder 100 2^a as weights are introduced thereunder.

19^a represents a nine-thousand-pound

weight placed on counterpoise 13 on which rider 19 is resting, thus elevating the card-holder 2^a.

Guide-bar 15 has on its face puncturing-pins 11^a 11^b, the lowest one of which is distant above the counterpoise 13, so as to punch zero on the upper half 12^b of card 12 when it is in position in the card-holder and no weights are placed on counterpoise 13. The remaining pins are placed, respectively, above the preceding one at a distance equal to the thickness of a ten-thousand-pound weight, and to the left so that a vertical line dropped through a puncturing-pin would be some fixed distance—as, for instance, one-eighth of an inch, as in Fig. 4—to the left of a like line dropped through the pin next beneath.

In Fig. 6, on half of card 12 marked 12^b the horizontal lines are spaced apart at a distance equal to the distance between the said vertical lines dropped through any two adjoining puncturing-pins 11^a 11^b. The vertical lines on 12^b are spaced apart by a distance equal to the thickness of a ten-thousand-pound weight. It will thus be seen that in this case the vertical lines denote thousands of pounds, while the horizontal lines denote ten thousands of pounds.

In this form of my device (shown in Figs. 1, 2, 3, 4, and 5) the operation of weighing is as follows: The load is placed on the scales and balanced in the ordinary manner. For instance, suppose the load to equal nine thousand two hundred and forty pounds. The counterpoise would be loaded with weights representing nine thousand pounds, which would elevate the card-holder 2^a by means of rider 19 to the position shown in Fig. 4. Card 12 is then inserted into card-holder 2^a in such a manner that its left-hand edge, as shown in Fig. 6, would be the top, the card facing inward. By pressing the flexible card-holder the portion 12^b of the card 12 would be punctured at the intersection of the horizontal line “0” and the vertical line “9.” When the weight of the load is determined by loading the counterpoise within a thousand pounds, the poise 2 on beam 1 is manipulated until the scale balances, when in this case the poise 2 would indicate two hundred and forty pounds on beam 1. The portion 12^a of the card 12 is then placed in card-holder 2 in the position shown in Fig. 6, but facing beam 1. By pressing push 7, 12^b would be punctured by the third pin 11 from the left on beam 1 at the intersection of horizontal line marked “2” with the vertical line marked “40,” or two hundred and forty pounds. Then reading from the two halves 12^a and 12^b of card 12 we have the total weight nine thousand two hundred and forty pounds.

My device may be applied to compound beams by the construction shown in Figs. 7, 8, and 9, in which figures the particular beam shown is such as is used on railway-scales. On poise 2 is fixed, by lugs 6^a 6^b, a secondary

beam 1^a, graduated to a thousand pounds, on which is mounted secondary poise 20, to which is fixed, by arm 21, the sliding bar 22, fitted with guide 22^a. Bar 22 has on its face a series of puncturing-points rising successively from right to left one-eighth of an inch, as in the figures, or any other fixed unit, and separated, respectively, by a distance equal to a graduation of a hundred pounds on beam 1^a. 75 23 is the ordinary roller mechanism by which poise 2 runs along beam 1. The rubber backing 9 is preferably cut away, so as to press against that portion of the card only which is marked off for registry, the form of the card 80 used in this case being shown in Fig. 10. 4^a is a plate attached to plate 5, upon which card 12 rests when in position. The pins 11 11 on beam 1, Fig. 7, have the same successive rise as like pins in Fig. 1, the first one being likewise so placed as to register “0” on the upper half of card 12, Fig. 10, when the poise 2 indicates “0” on beam 1, Fig. 7, and each successive pin being to the right of the preceding one by a distance equal to the graduations of a thousand pounds. It follows that the horizontal lines in the upper half of card 12, Fig. 10, which are separated by a distance equal to the rise in the series of pins denote tens of thousands, while the vertical lines 95 which correspond to the graduation of the beam denote thousands. In the case of the lower half of card 12, Fig. 10, the horizontal lines are separated by a distance equal to the unit of rise of series of pins 11^b 11^b on beam 10^a 22, thus denoting hundreds of pounds, while the vertical lines correspond to the graduation on beam 1^a and accordingly denote tens of pounds and subdivisions thereof. In registering weights—for instance, seventy-four 105 thousand one hundred and sixty pounds—in this form of my device the poises are moved into the position of balancing and the card inserted face inwardly in the card-holder, seventy-four thousand pounds is indicated on 110 the beam 1, Fig. 7, in like manner as two hundred and forty pounds was indicated on beam 1, Figs. 1, 2, and 3, the scale, however, in this case, of course, being graduated in thousands of pounds instead of hundreds. When 115 the secondary poise is moved along beam 1^a, the bar 22 moves therewith, carrying pins 11^b 11^b past the divisions on the lower half of the card. When the secondary poise stands at “0,” the first punch to the right would be 120 opposite the intersection of the two “0” lines on the card when it is in position for puncturing. As the poise is moved to the right the said punch traverses successively the divisions of the card on horizontal line “0” until 125 a hundred pounds is reached, when the first punch passes beyond the divisions and the second punch traverses the horizontal line marked “1” until it reaches the vertical line marked “60,” when in this case the scale 130 would balance. The card is then punched, the upper half recording seventy-four thou-

sand pounds and the lower half one hundred and sixty pounds, or in total seventy-four thousand one hundred and sixty pounds.

Figs. 11 and 12 show a modification of the device as applied to a compound beam, in which a pointer 24 instead of a sliding bar 22 is fixed on arm 21. When secondary poise 20 indicates "0" on secondary beam 1^a, the card being in position, said card having on its lower half a scale graduated to correspond to 1^a, Fig. 13, pointer 24 is opposite "0" on the card and punctures the card at that point when the push 7 is pressed. As the secondary poise is advanced along 1^a the pointer correspondingly advances along the card and will punch accordingly when the card is advanced against it.

Having described my invention, I claim—

1. In a recording-scale, a beam having registering-pins thereon spaced at graduated horizontal and vertical distances.

2. In a recording-scale, a beam having registering-pins thereon spaced horizontally according to the graduations on the beam and vertically by a predetermined unit.

3. In a recording-scale, a beam; a counterpoise hung on said beam; a guide-bar carried by said counterpoise and registering-pins on said guide-bar spaced at graduated horizontal and vertical distances.

4. In a recording-scale, a beam; a counterpoise hung on said beam; a guide-bar fixed to said counterpoise and registering-pins spaced thereon vertically corresponding to the weights used on said counterpoise and horizontally by some predetermined unit.

5. In a recording-scale, a beam; a counterpoise hung on said beam; a guide-bar fixed to said counterpoise; registering-pins on said guide-bar, spaced at graduated horizontal and vertical distances; a card-holder sliding on said guide-bar; a card adapted to fit in said card-case and receive the imprint of said registering-pins, and means of advancing said card against said pins.

6. In a recording-scale, a beam; a counterpoise hung on said beam; a guide-bar fixed to said counterpoise; registering-pins spaced on said guide-bar vertically corresponding to the weights used on said counterpoise and horizontally by some predetermined unit; a card-holder sliding on said guide-bar; a card adapted to fit in said card-case and receive the imprint of said registering-pins, and means for advancing said card against said pins.

7. In a recording-scale, a primary beam fitted with registering-pins; a primary poise mounted thereon; a secondary beam on said primary poise; a secondary poise mounted on said secondary beam; a punching-pin actuated by said secondary poise; a card so divided by horizontal and vertical lines as to receive the imprint of the pins on the primary beam and the pin or pins actuated by the secondary poise and a card-holder fitted to contain said card and advance it toward said beam.

8. In a recording-scale, a beam having registering-pins at graduated horizontal and vertical distances and a card carried by the poise adapted to receive the registering-marks of 70 said pins.

9. In a recording-scale, a beam, registering-pins spaced at graduated horizontal and vertical distances on said beam, a poise adapted to be used as a card-holder; a card adapted 75 to fit in said poise and means for advancing said card against said pins.

10. In a recording-scale a beam, a counterpoise hung on said beam, a guide-bar mounted on said counterpoise; registering-pins 80 spaced at horizontal and vertical distances on said guide-bar; a card fitted to receive the imprint of said pins and means of applying said card to said pins.

11. In a recording-scale, a beam, register- 85 ing devices spaced on said beam at graduated horizontal and vertical distances.

12. In a recording-scale, a primary beam having pins graduated at horizontal and vertical distances thereon; a primary poise 90 mounted on said primary beam; a secondary poise carried by said primary poise and a registering member actuated by said secondary poise and fitted with registering pin or pins.

13. In a recording-scale, a primary beam 95 having pins graduated at horizontal and vertical distances thereon; a primary poise mounted on said primary beam; a secondary poise carried by said primary poise and a puncturing-pointer actuated by said secondary poise.

14. In a recording-scale a beam having register-pins spaced thereon and a card fitted to receive the impress of said pins and graduated with horizontal and vertical lines, one 105 series of lines denoting multiples of the other series.

15. In a recording-scale, a primary beam having registering-pins thereon; a primary poise mounted on said primary beam; a secondary poise carried by said primary poise; a registering member actuated by said secondary poise and fitted with registering-pins, and a card fitted to receive the impress of 110 said pins and divided into two sections, each 115 section being graduated by horizontal and vertical lines, one series of said lines denoting multiples of the other series, and the graduations on one section of said card denoting multiples of the graduations on the other section. 120

16. In a recording-scale, a beam; a poise mounted on said beam; a bar actuated by said poise having on its face pins spaced vertically and horizontally at graduated distances.

In testimony whereof I have hereunto set my hand this 12th day of August, A. D. 1896.

MATTHEW H. REED.
